UNITED STATES PATENT OFFICE.

CHRISTINE PETERSEN, OF EVANSTON, ILLINOIS.

CORSET.

1,263,800.

Specification of Letters Patent.

Patented Apr. 23, 1918.

Application filed May 18, 1917, Serial No. 169,420.

To all whom it may concern:

Be it known that I, CHRISTINE PETERSEN, a citizen of the United States, residing at Evanston, in the county of Cook and State of Illinois, have invented certain new and useful Improvements in Corsets, of which the following is a specification:

This invention relates to corsets, and it has for its object to provide an improved attachment which may be applied to or form a part of corsets of various kinds, for supporting the abdominal and pelvic organs of the wearer, and which assists in producing desirable fashionable lines. The nature of the device is such that it tends to produce an erect posture and graceful carriage, holding all organs in normal position, preventing prolapsus and shortening and strengthening pendulous muscles, giving relief in ptosis, back-ache and other injurious results following.

The invention is illustrated in the accompanying drawing, in which—

Figure 1 is a front view of a corset provided with the improvement;

Fig. 2 is a plan of one of the pieces or parts of the supporter removed from the corset;

Fig. 3 is a front elevation of a corset of the type which is laced at the back, showing the manner of adjusting the supporter.

Figs. 4 and 5 are details in plan of modifications.

In Fig. 1 a laced-in-the-front corset is shown, and the device is most easily applied to a corset of this type. The corset is indicated at 6, the front lacings at 7, and the front hooks at 8, of ordinary or suitable construction.

The attachment in one form comprises two similar sections or pieces of material, preferably rather heavy, indicated at 9. At the front end each piece has a row of eyelets 10 and at the lower front corner a depending tab 21 with a button 11. At the lower rear corner is a backwardly extending tab or flap 12, inclined downwardly, and having a button 13, near the rear end. The upper edge of the piece may be cut straight across as shown at 14. The lower edge between the tabs 21 and 12 is cut on a curve, as indicated at 15. Laces 20 connect the two front ends of the sections, being passed through the eyelets 10, and by means of

these laces the attachment can be adjusted as desired.

Each of the pieces referred to is stitched or otherwise attached, intermediate its length, to the side or side piece of the corset, as indicated at 16, the connection being preferably made at or near the upper edge of the piece 9, with the lower edge free. The point of attachment to the corset is preferably at or about the lower front part 60 of the corset, in front of the point of the hip, and the curved loose edge 15 enables the device to be closely and smoothly fitted over the hip and the bend of the thigh. A flannel thigh strip 17 is connected by loops 70 at its ends to the buttons 11 and 13 and extends around the thigh of the wearer and serves the purpose of holding the device in close fitting relation or position below or under the abdomen.

When used with a corset which laces in the back, as shown in Fig. 3 the front pieces of the corset are provided with openings or eyelets 18 through which the ends of the laces 20 are passed, and when the attachment is drawn up to the required tightness these laces are tied in front, on the outside of the corset. The pieces 9 are attached to such a corset in the same way as above described.

In the use of the device the corset is first placed on the wearer and the thigh straps connected. Then by tightening the laces 20 the attachment is drawn up or under the lower part of the abdomen, and acts to lift 90 and support the same. After this the corset can be closed and adjusted as desired, and the attachment resists any tendency of the corset to force the abdomen down to an unhealthy or uncomfortable position, and enables the corset to be drawn tighter around the hips than would otherwise be the case. In the use of the device with the corset which is laced at the back, the attachment may be drawn up after the corset is closed, 100 by pulling the strings 20 and tying the same outside.

In the modification shown in Fig. 4, the attachment consists of four pieces, two for each side, a front piece 30 and a rear piece 105 31. These pieces are sewed opposite each other to the inside of the corset, to occupy the same relative position and perform the same functions, as the single piece 9, the front piece 30 having the tab 21 and button 110

11 and the rear piece 31 having the tab 12 and button 13, to which the thigh straps 17 are connected as above described, and for the same purpose.

5 In Fig. 5, the attachment, instead of being made in separate pieces as above described, is made integral with sections of the corset. That is, each of one of the front pieces 32, of the corset is provided with a 10 front extension piece 30^a and a rear extension piece 31^a, having buttons 11 and 13 as above described, and for the same purpose. These extension pieces are cut from the same 15 piece of material as the front section 32, and when the front piece is set into the corset, as a part thereof, the extension pieces form flaps on the inside, hanging loosely, and adapted to be connected by laces 20 for the purpose above described.

20 The invention is not limited to the particular forms herein shown and described, but various other modifications are possible within the scope of the claims.

25 I claim:

1. The combination with a corset, of an abdominal supporter comprising two side pieces attached intermediate their ends to

the inside of the corset at the sides thereof, both ends of each of the said side pieces being free from the corset, adjustable connections between the front ends of said pieces, and a thigh strap connecting the front and rear ends of each piece.

2. The combination with a corset, of an 30 abdominal supporter comprising two elongated side pieces attached between their ends to the interior of the corset at the sides thereof, each side piece having tabs at their front and rear lower corners, thigh straps 35 connected to said tabs, and connections between the front ends of said pieces, above the front tabs.

3. A supporting corset having a side part 40 forming a section of the corset side and secured in fixed relation to the other sections thereof, said part being provided with flaps at its front and rear edges, on the inside of the corset, for the purpose stated.

In testimony whereof, I affix my signature in presence of two witnesses.

MRS. CHRISTINE PETERSEN.

Witnesses:

KAREN D. ROLLERT,
I. H. SNYDER.
